WORK-HOLDER

Daniel H. Chason, Elizabeth, N. J., assignor to
The Singer Manufacturing Company, Eliza-
beth, N. J., a corporation of New Jersey

Application January 10, 1935, Serial No. 1,150

1 Claim. (Cl. 223—110)

This invention relates to work-holders and more particularly to work-holders for seamstresses, tailors, and the like that may be attached to a sewing machine cabinet or table and which holds one end or side of cloth or other flexible material when it is desirable to subject the material to tension for the purpose of ripping a seam or performing other operations thereon.

5 The several features of the present invention will be clearly understood from the following description and accompanying drawing in which:

Figure 1 is a perspective view of a work-holder embodying the invention in its preferred form.

10 Figure 2 is a rear side elevation.

Figure 3 is a detail sectional view taken along the line 3—3 of Figure 2.

Figure 4 is a rear side elevation, partly in section, to show the relation of the parts.

15 In the embodiment shown, my improved work-holder comprises a clamp 1 of substantial U-shaped formation, the upper limb of which is adapted to engage a table-top 2. The lower limb has a threaded opening therethrough in which is threaded a clamping-screw 3 having a swivel head 4 for engagement with the under face of the table. The clamp is lined with felt or other soft fibrous material as shown at 1' in Figure 2.

20 Formed integral with the clamp 1 is a lower jaw 5 having a lateral extending clamping portion 6. Pivotal secured by the pivot-pin 7 to the lower jaw 5 is an upper jaw 8 having on its free end a laterally extending clamping portion 9 which cooperates with the clamping portion 6. The other end of the upper jaw 8 is bifurcated

25 to form the arms 10 and 10' which embrace an eccentric 11 pivotally secured to the fixed lower jaw 5 by the pivot-pin 12. Formed integral with the cam 11 is a finger-lever 13.

From the foregoing it will be evident that when the finger-lever 13 is raised the eccentric 11 acts on the arm 10' to positively swing the upper jaw 8 in a counter-clockwise direction about its pivot to open the jaws and when the lever 13 is depressed the cam 11 acts on the arm 10 to positively close the jaws.

Having thus set forth the nature of the invention, what I claim herein is:—

25 A work-holder comprising a sheet-metal body portion bent flatwise of itself into a U-shaped clamp to embrace the edge of a table-top, a clamp screw threaded into the lower limb of the U-clamp, the upper leg of the U having a flat up-standing stationary member extended at one side in the plane of said member to form an upwardly curved limb the free end of which is bent over laterally to form a clamping jaw, a movable sheet-metal member having a body portion pivoted to said stationary member and extended at one side to form a downwardly curved limb the free end of which is bent laterally to form a clamping jaw opposed to the first mentioned clamping jaw, the body portion of said movable member being formed with a slot, and a hand operated eccentric member pivoted to the first mentioned member and engaging the walls of said slot.

DANIEL H. CHASON.
